UNITED STATES PATENT OFFICE.

MATTHEW E. CAMPFIELD, OF PITTSBURG, ASSIGNOR TO THE BROWN SPECIALTY MANUFACTURING COMPANY, OF ETNA, PENNSYLVANIA.

MACHINE FOR TRUING AND DRESSING WRENCH-BLANKS.

SPECIFICATION forming part of Letters Patent No. 395,213, dated December 25, 1888.

Application filed February 23, 1888. Serial No. 264,929. (No model.)

To all whom it may concern:

Be it known that I, MATTHEW E. CAMPFIELD, a citizen of the United States, residing at Pittsburg, in the county of Allegheny and 5 State of Pennsylvania, have invented certain new and useful Improvements in Machines for Truing and Dressing Wrench - Blanks; and I do hereby declare the following to be a full, clear, and exact description of the invention, such as will enable others skilled in the art to which it appertains to make and use the same.

My invention comprises a machine for dressing and sizing wrench-blanks and other 15 articles by which the two opposite sides of the shank are simultaneously planed or dressed and the shank brought to the required thickness at a single operation.

The invention consists, broadly, in passing 20 the blank to be dressed between two planing-cutters, which are provided with cutting-teeth, and which are arranged at a distance apart corresponding with the thickness which the finished article is to have.

25 In the accompanying drawings, which illustrate my invention, Figure 1 is a plan view of the machine. Fig. 2 is a longitudinal section of the same on the line 2 2, and Fig. 3 is a transverse section on the line 3 3.

30 The same reference-letters designate the same parts in all the figures.

The frame of the machine is composed of parallel bars A A, which are suitably secured together at their ends and are supported upon 35 legs a a a a. The bars A are a sufficient distance apart to receive between them the reciprocating plunger d e, by which the blanks to be dressed and sized are forced forward between planing-cutters f f. The cutters f f

40 are flat steel blocks, which are provided on their inner faces with backwardly-inclined cutting-teeth f', which plane the sides of a blank forced through between them. The teeth are formed at an angle running from

45 the top downward and forward, whereby they have a tendency to draw and hold the blank down as it is being forced through. Preferably, though not necessarily, as an essential feature of the invention, cutting-teeth f'' are 50 also formed on the upper edges of the blocks

f. These are for the purpose of dressing the under side of the fixed jaw or wrench-head, and they are caused to act by the tendency of the teeth f' to draw the blank down. When the plunger is at the limit of its rearward reciprocation, there is a sufficient space between it and the cutting-teeth to receive the blank to be dressed, which is placed therein in vertical position, as indicated in Fig. 2. Then by the forward reciprocation of the plunger it is forced through between the cutters f into an open space (marked x) in front of the teeth, when it is ready to be removed from the machine. 55 60

The cutter-blocks f are preferably set with 65 their front ends a little closer together than their rear ends, so that the teeth f' will act successively.

The plunger consists of a block, e, which fits snugly between the bars A A, and has lateral 70 top and bottom flanges, by which it is retained in place, and a forwardly-projecting arm or blade, d, of a thickness to pass between the cutters f f. It is reciprocated by an eccentric, C, on a transverse driving-shaft, 75 c', which passes through the bars A A at the rear end of the machine, the eccentric being connected with the plunger by an arm or pitman, c, on the collar c''. The block e has a socket in its rear face to receive the end of 80 the arm or pitman c, and the two are connected by a transverse pin or bolt, e'. The socket is flared outwardly and the end of the arm c is rounded, as represented in Fig. 2, to permit the necessary vibration of the arm. 85 The shaft c' carries a driving-pulley, B, through which power is applied.

The bars A A are tied together by top and bottom tie-rods, a' a'', to prevent their springing apart when the machine is in operation. 90

The arm d of the plunger is supported and guided at its front end by laterally-projecting arms d', which project into horizontal guide-ways d'' below the bars A.

While I have described a machine with two 95 side bars, A A, one pair of cutters, f f, and one plunger, I show in my drawings a double machine arranged and constructed to dress the four sides of a wrench-blank. Since the shank is thicker in one direction than in the 100

other, two machines are required to dress the four sides, and therefore, for convenience and economy of shop-room, I make the machines double, as represented in the drawings, with 5 two pairs of cutters and two plungers. When so constructed and arranged, the two eccentrics are set opposite to each other on the shaft, so that the two plungers will reciprocate in opposite directions and will therefore 10 operate alternately.

Evidently the capacity of the machine may be multiplied to any extent desired without departing from the spirit of the invention.

While I show and describe eccentrics for 15 operating the plungers, evidently cranks may be used instead, these being well-known mechanical equivalents, and I therefore desire to have it understood that the invention is not to be limited to the use of eccentrics.

20 Having now described my invention, I claim as new—

1. In a machine for sizing and finishing wrench-blanks and other articles, the combination, with the parallel bars A A, of oppositely-arranged planing-cutters *ff*, facing each other and affixed to the inner sides of the said bars, and a reciprocating plunger guided between said bars and adapted to force the blanks between said cutters, substantially as 25 shown and described.

2. In a machine for sizing and finishing wrench-blanks and other articles, the combination, with the parallel bars A A, of oppositely-arranged planing-cutters *ff*, facing each other and affixed to the inner sides of said 35 bars, a reciprocating plunger guided between said bars, a driving-shaft, an eccentric or its mechanical equivalent on said shaft, and a connection between said eccentric and plunger, substantially as shown and described. 40

3. In a machine for sizing and finishing wrench-blanks and other articles, the combination, with the parallel bars A A, of oppositely-arranged planing-cutters *ff*, facing each other and affixed to the inner sides of said 45 bars, said cutters each having a series of downwardly and forwardly inclined cutting-teeth, and a reciprocating plunger guided between the bars A A to force the blanks between the cutters, substantially as shown and 50 described.

In testimony whereof I affix my signature in presence of two witnesses.

his
MATTHEW E. X CAMPFIELD.
mark.
